UNITED STATES PATENT OFFICE.

ROBERT R. LAWSON, OF NEW YORK, N. Y., ASSIGNOR TO MARY C. GORMAN, OF NEW YORK, N. Y.

ENVELOP-FASTENER.

SPECIFICATION forming part of Letters Patent No. 752,402, dated February 16, 1904.

Application filed March 18, 1903. Serial No. 148,343. (No model.)

To all whom it may concern:

Be it known that I, ROBERT R. LAWSON, a citizen of the United States, and a resident of New York city, in the county of New York and State of New York, have invented certain new and useful Improvements in Envelop-Fasteners, of which the following is a specification.

My invention relates to a new and useful improvement in envelop fasteners or clips to secure the flap of an envelop more firmly to the body of the same.

It refers more especially to that type of envelop which it is desired to fasten securely, but not to seal, so that the envelop may be opened and closed again without injury to it or to the fastening, and it is similar in action to those envelopes which are closed and fastened by a device having metal prongs adapted to project 20 through an opening in the flap and to be bent over and against the body of the same to fasten it when closed. The difficulty which has heretofore existed with devices of this character is that such fastenings are put through 25 the body of the envelop in such a manner that when pressure or strain is brought to bear against it by reason of the fact that the envelop is filled with goods or otherwise there is not resistance enough or strength enough 30 to keep it from breaking loose or tearing away from the envelop or package, or if it works loose and the package is torn open in consequence it permits the contents to be lost in transit, or because it is loosely attached to the 35 envelop which it fastens it works backward and forward and its metal base has a tendency to scratch the goods against which it presses and with which the envelop may be filled. A further difficulty has resulted from the tendency 40 of such devices to slip or move about in the act of bending the prongs thereof to fasten the flap in place.

The present device is designed to overcome such disadvantages and to provide a small and effective envelop fastening or clip in which strength is combined with convenience and economy.

I take a stout paper base which is cut in

the form of a disk, which paper may be reinforced with cloth for strength, the upper surface of which is gummed. Upon this paper disk I set the base of a brass clip similar to the well-known McGill fastener, which consists of a piece of light brass or metal bent in the form of a T, the stem of which may be 55 bent down on either side over the base. Through the stem or prongs of this brass member I push a smaller disk in form as is shown in Figure 2 of the drawings, which second disk has a hole in the center to admit the passage 60 of the stem of the brass member through it. The upper plane of this second paper disk is also gummed. When the brass member is placed upon the circular paper disk, the second disk that goes over it is moistened slightly 65 and adheres to the gummed surface below, and this holds the head of the brass member firmly, making a fastener for use as I have indicated.

The envelop is made, preferably, with its flap doubled and gummed together in order to increase its strength, and the hole which receives the stem of the clip is cut through it, and a hole in the upper body of the envelop is also made to correspond with that in the flap when the same is bent over the body. The fastener 75 is used by moistening the upper surface of its base and then pressing it from the inside through the hole in the upper body of the envelop, to which body it firmly adheres, with its prongs projecting and ready to be pushed 80 through the hole in the flap of the envelop and the prongs bent over in the ordinary manner, fastening it.

My invention is clearly illustrated in the accompanying drawings.

Fig. 1 is a top plan view of the complete device detached from the envelop or receptacle. Fig. 2 is a cross-sectional view taken through the center of Fig. 1. Fig. 3 is a paper disk or base. Fig. 4 is a smaller disk 90 or base of slightly-different form with a hole through the center. Fig. 5 is a section of an envelop, showing in outline the device attached to its body. Fig. 6 is a view of a section of the envelop with the flap closed and 95 held by the brass members of the device.

In operation the base of the T-shaped metal member is placed upon the paper disk or base, (indicated by Fig. 3,) one surface, called the "upper" surface, being covered with adhesive gum. A second base is indicated by Fig. 4, slightly smaller than the first base, through the center of which is a hole C, and the stem of the brass member is passed through the hole C of the smaller disk, which smaller disk is made to adhere to the larger disk by means of the adhesive gum thereon, clasping the head of the T-shaped brass member between the two, and forming thereby a substantial head. This device is then used to seal an envelop in the manner indicated by moistening the exposed surface of the gum on the larger paper disk not covered by the surface of the smaller disk, and the stem of the device is passed through a hole in the body of an envelop to be sealed from the inner side thereof, as shown in Fig. 5, and the hole e, as shown in the flap of the envelop in Fig. 5, is then brought down over the stem of the metal member which protrudes through the hole d, and the stem thus turned down to seal the envelop, as shown at e in Fig. 6.

Having thus described my invention, I claim—

1. An envelop-fastening device comprising a metallic member of a T shape, the stem of which consists of two prongs which may be bent laterally in an inverse direction, the head of said member being confined between two disks, the upper surface of said disks being covered with an adhesive gum, substantially as described and for the purposes mentioned. 35

2. An envelop-fastening device comprising a metal member of a T shape having for its stem duplicate prongs, each of said prongs being in excess substantially of one-half the 40 length of the body member, base or head thereof, the said base or head being placed between two paper disks, the upper surface of said disks being covered with adhesive gum for the purposes mentioned and as described. 45

Signed at New York, in the county of New York and State of New York, this 14th day of March, A. D. 1903.

ROBERT R. LAWSON.
